ATTORNEYS

UNITED STATES PATENT OFFICE.

EUGENE C. McELHANY, OF KALAMAZOO, MICHIGAN.

TAMBOURINE.

Application filed May 3, 1924. Serial No. 710,823.

To all whom it may concern.

Be it known that I, EUGENE C. McELHANY, a citizen of the United States of America, and a resident of Kalamazoo, in the county of Kalamazoo and State of Michigan, have invented a new and Improved Tambourine, of which the following is a description:

My invention has for its general object to provide a tambourine improved in various particulars having in view the provision of an assemblage of jingle elements so positioned as to produce effective jingling.

A further object of the invention is to provide in association with the jingle elements a novel castanet assemblage so associated with a sounding board as to be effective in the playing of the tambourine.

The invention also has for an important object to provide a tambourine effectively braced to possess the maximum strength and at the same time to present a highly attractive appearance.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a plan view of a tambourine embodying my invention;

Figure 2 is a transverse vertical section taken as indicated by the line 2—2, Figure 1.

In constructing a tambourine in accordance with my invention, a three-sided frame 10 is provided, the sides and angles being curvilinear. Associated with each curvilinear side of the frame 10 is a brace 11 the ends of which are held to the frame 10 through the interposition of spacing blocks 12 between the ends of a brace 11 and the adjacent curvilinear side of the frame 10. Thus, a brace extends across the base of the curve represented by the adjacent curved side. Along one edge, which in practice is the back edge of the tambourine, is a reinforcing strip or bead 13. At each angle of

the frame is a strengthening angle piece 14.

Each brace 11 is formed with a longitudinal slot 15 crossed by pins 16 on which are loosely mounted jingle elements 17, said slot being wide enough to allow movement of the elements 17 along the pins 16 in addition to the turning movement permitted said elements. Thus, the braces are utilized for mounting the jingle elements 17 within the frame 10.

In addition to the jingle elements 17 I provide exterior jingle elements as follows:

Metallic strips 18 are provided at each side of the frame 10 extending lengthwise thereof and secured at their ends by rivets 19 or other equivalent means. The strips 18 are offset for their major portions and the space between a strip 18 and the exterior surface of the adjacent side of the frame 10 is crossed by pins 116 corresponding with the pins 16. On the pins 116 are loosely turnable and slideable jingle elements 117.

The jingle elements 17 and 117 are disposed in pairs on each pin 16 or 116 and it will be observed that by the described arrangement the jingle elements 17 are in planes at right angles to the planes of the jingle elements 117 whereby effective jingling will be produced by one series of jingle elements or the other irrespective of the direction of movement imparted to the tambourine by the player. Extending from that brace 11 at the base of the triangular figure presented by the braces is a sounding board 20 extending from said base to the apex of the frame 10 and therefore to the convergent ends of the remaining two braces 11. Said board 20 is of wood and attached thereto are a series of flat castanets 21 also of wood. The castanets 21 are of various sizes to give forth various sounds and each castanet is secured to the board 20 detachably, there being employed for the purpose in the illustrated example a thread or cord 22 laced through short shanks 122 on the castanets and through the sounding board 20. The securing by the threads or cords 22 is done in such a manner as to lend flexibility to the castanets 21 to flap with the said cords.

as a hinge and thereby contact flatwise with the sounding board when the tambourine is shaken.

At the apex of the generally triangular frame 10 is a bearing 23 on said frame and over the convergent ends of the adjacent braces 11.

It will be apparent that the castanets, by the above-described essentially triangular arrangement, are easily removable from the sounding board and also it is practical to manipulate the tambourine, for sounding the various elements, with one hand, which is an advantage that will be appreciated by players of tambourines. The triangular and braced assemblage, as described, results in increased strength in addition to facilitating the manipulation of the tambourine with the fullest effect.

I would state in conclusion that while the illustrated example constitutes a practical embodiment of my invention, I do not limit myself strictly to the exact details herein illustrated, since, manifestly, the same can be

considerably varied without departure from the spirit of the invention as defined in the appended claims.

Having thus described my invention, I claim:

1. A tambourine including a frame, presenting a plurality of sides at angles to each other, and braces extending across the tambourine adjacent to each side of the frame; together with jingle elements carried by said braces. 30

2. A tambourine having a frame, and braces arranged in the frame adjacent to each side at the interior of the frame, jingle elements supported by the braces, jingle elements at the exterior of the frame at right angles to the first-mentioned elements, and means supporting those elements at the exterior of the frame. 35

3. A tambourine having a series of jingle elements, and a second series of jingle elements disposed in planes at angles to the first-mentioned jingle elements. 40

EUGENE C. McELHANY.
